UNITED STATES PATENT OFFICE.

OSCAR A. SMITH, OF EAST CLEVELAND, OHIO, ASSIGNOR TO THE NATIONAL ACME COMPANY, OF CLEVELAND, OHIO, A CORPORATION OF OHIO.

NUT-CASTELLATING MACHINE FOR SMALL NUTS.

Application filed October 14, 1921. Serial No. 507,662.

This invention relates to nut castellating machines, the object of the invention being to provide an improved machine of this class, which, while it can be used with comparatively large nuts, is nevertheless more particularly adapted for castellating very small nuts, such as one-quarter inch and smaller, the present invention being an improvement in part upon the machine shown and described in Patent No. 1,157,258 dated October 19, 1915 to Smith and Rindfleisch, assignors to The National Acme Company, of Cleveland, Ohio.

The machine shown and described in that patent was a very successful machine, and many of them have been in operation for a number of years, but certain features thereof, as in all automatic machinery, are capable of improvement.

The present improvement has to do largely with the punching mechanism, the object of the invention being primarily to provide a punch which, like the machine of the patent hereinbefore referred to, is horizontally carried but by improved means, whereby more advantageous results and a stronger punch are obtained.

One of the objects of the invention also is to so support the punch that the necessity of using a ram extension, as was necessary in the patent referred to, is avoided.

The main object therefore, of the present improvement, is the provision of an improved punching mechanism, wherein a horizontally supported punch may be used in combination with a vertically movable slide, with which the ram is adapted to cooperate so that, without the use of an auxiliary ram extension and without the necessity of pivotally supporting the punch, a very effective nut castellating machine is provided, primarily adapted for small nuts.

Thus, in the present improvement, the blow of the ram is imparted to a vertically movable slide carrying the punch in a horizontal position very close to the effective punching point of the punch, while at the same time by means of this vertically movable slide, the punch is movable in a straight vertical path relative to the work to be done, so that, in consequence a much more direct action of the punch upon the blank is obtained and therefore with better results.

In the drawings accompanying and forming a part of this specification, Fig. 1 is

a plan view of that part of the machine taken below the ram operating mechanism; Fig. 2 is a front view of the machine; Fig. 3 is a side view thereof, part of the press being shown in dotted lines and a part thereof broken away; Fig. 4 is a horizontal cross sectional view of the machine taken on line 4—4 Fig. 3; Fig. 5 is a vertical cross sectional view of the machine taken on line 5—5 Fig. 4; Fig. 6 is a view of a nut and the punch for castellating it, it illustrating in dotted lines the movement of the punch; and Fig. 7 is a perspective view of one form of die that may be used for carrying the nut blanks.

Similar characters of reference indicate corresponding parts in the several figures of the drawings.

The present machine has to do with the punching of blanks, such as nut blanks, having an axial hole therethrough, and like the prior machine referred to, the several elements making up the machine are applied to a press of any suitable style, a detailed description thereof being deemed unnecessary herein, except in so far as it has to do with the improved features of the said machine.

The punch press shown comprises the usual stand or base 2 having the usual power driven wheel, a shaft on which the wheel is mounted, and ram 3, it not being deemed necessary herein to show the treadle and connecting means therebetween, and the usual clutch carried by the shaft.

The die carrying means and the means for indexing the die carrying means to successively index the nut blank through the several stations, the locking means for locking the die carrying means, and the means for successively feeding nut blanks to the die are or may be substantially similar in their general description and mode of operation to that shown in the patent hereinbefore referred to, and therefore only a brief description of those parts is deemed necessary herein.

The die 20 (see Fig. 7) is provided with the necessary axial opening or bore 21, and rim or flange 22, and is provided with as many slots 23 as it is desired to punch in the nut or other piece to be slotted, and in the present instance six of these slots 23 are shown. These slots communicate with the axial opening or bore 21, and are of a suitable

depth to properly permit the nut to be castellated and the slugs to pass away from the nut. The bore of the die receives the nut blank to be castellated, as illustrated in Fig. 5. The die is suitably supported by a die carrier, which may be in all respects, if desired, similar to that shown and described in the said patent referred to, and this die carrier is provided with as many indexing and locking grooves or recesses 30 as there are slots in the die.

In other words, the number of grooves or recesses 30 in the die carrier or holder usually correspond with the number of slots 15 in the die, and of course the latter correspond in number with the number of slots or castellations the nut is to have. This die carrier or ring, generally called an indexing ring, since it is by this means in part that the die is indexed, although obviously the nut could be rotated in the die if found desirable, and to which the die is properly secured by suitable means to prevent movement of the die independently of the 25 ring, is indexed automatically by a suitable indexing means. This indexing means is in a general way similar to that shown in said patent hereinbefore referred to, and briefly comprises an indexing lever 30 having at its end an indexing pin 52 in position to project successively into each of the slots or recesses of the indexing ring. This indexing lever 50 is actuated by an auxiliary rod or lever 53, the upper end of which is secured to a cross slide 54 of the ram. The locking mechanism for locking the indexing ring in its several stations may likewise be similar to that shown and described in the said patent, and consists in 40 part of a locking bolt 44 pivoted on a pin 45 so that the bolt can swing into and out of the indexing slots, it being swung into position to enter one of these slots or recesses each time the ring is indexed. This bolt is of course withdrawn from its slot to permit the proper operation of the indexing ring, and its die, and this is accomplished by a suitable cam 46 carried on the fly wheel shaft, and which cam cooperates with a lever 48 45 pivoted to the framework of the press, the lower end of the lever being in position to engage this lock bolt, so as to swing it free of the slot or recess in the indexing ring, some suitable means similar to that shown in 50 said patent, being provided for insuring the proper cooperation of the lock bolt 44 with the slots of the indexing ring. As the locking mechanism may be substantially similar to that shown in the said patent, it will be 55 obvious that in practice a part of the ram mechanism may be provided with a locking tooth, such as that referred to in said patent, for further positioning and also locking the said ring against movement.

In the present improvement, as in the

patent referred to, the nut blanks are semi-automatically fed to the die and punched, and for this purpose a suitable magazine 70 is provided properly bolted to a stationary part of the machine. The nut blanks are 70 so held in the magazine that they will drop freely into position before a feed rod 73 controlled by a handle 74 pivoted to the front of the machine. The end of the feed rod of course will be of a size suitable to 75 fit the particular size of the nut to be castellated, and will therefore vary according to the different sizes of nuts, as will also the size of the punch. On pushing the handle toward the machine, it will enter into 80 the hole of the lowermost blank of the magazine, and as the blank is pushed forward by the continued forward movement of the feed rod, it is by suitable means fed completely on to the rod, and thus the blank 85 is carried into the die in the manner shown in Fig. 5, in readiness to be castellated, and after it is castellated completely the rearward movement of the handle will withdraw the castellated nut from the die, whereupon 90 it may be removed in similar manner to that shown and described in said patent.

In fact, as hereinbefore stated, the several mechanisms for indexing the die and locking its carrier and for feeding and removing the nut blank from the carrier, may be in all respects similar or substantially similar to that shown and described in said patent, and therefore a further detailed description thereof may be had by reference to that 100 patent, and is thus deemed unnecessary herein.

Suitably bolted to the bed 2 of the press directly in back of the die holding mechanism hereinbefore referred to, is a knee block 105 4, and vertically machined in the front face of this knee block is a suitable dove-tailed slideway 5, in which slideway is slidably housed by means of a key 6, and suitable adjusting screws 7, a vertically movable dove-tailed slide 8, one part of the top of which is located in position to be engaged by the ram post and thus shift the slide downwardly with the punch carried thereby 110 to castellate the nuts. This dove-tailed slide 8 has a horizontal bore in line with the center of the die, and in this bore is housed a die holding shaft 9, upon the rear end of which (see Fig. 5) is mounted a flanged or collar portion 10 secured to the slide 8. Directly in front of this collar portion is milled a suitable flat portion 11. A set screw 12 is tapped into the slide in such position as to rest against this flat portion and hold the shaft in position. An adjusting screw 12' is centrally housed in the rear end of this shaft in position to engage a pin 13 located between this adjusting screw and the punch, and filling the space between the two, and therefore termed herein a fill 130

pin, and by this means the punch 14 may be adjusted toward and from the die or the blank. The punch 14 is secured in this die holding shaft by suitable means, as set 6 screws 15.

The punch is provided at its end with a forwardly or horizontally projecting tooth 14^a of small size with relation to the size of the punch body and normally located within 10 the center opening of the blank. This construction is advantageous particularly where very small blanks are to be castellated, and also enables the size or diameter of the punch body to be independent of the 15 size of nut blank.

Furthermore, by reciprocating the punch in a straight vertical line while the longitudinal axis of the blank is in horizontal 20 position, the strain of cutting will be distributed evenly along the bottom of the tooth, thereby minimizing the tendency of the tooth to chip or break off.

An upper portion of the dove-tailed slide is machined parallel, as at 16, with the bore, 25 that is provided with a straight face, which is parallel with the axis of the bore, and constitutes the surface for the ram 19 to strike when operated. While the bore of the punch holding shaft is shown herein as circular for the reception in the present instance, of a round punch, it will be obvious 30 that the bore may be of other shapes to fit other shapes of punches.

From the foregoing it will thus be observed 35 that I have provided a horizontally supported punch carried by a vertically movable slide so that the slide and its punch may be reciprocated in a straight path to castellate the nuts, and that by providing 40 this vertically movable slide the power of the ram may be utilized with greater effect than was possible in the patent hereinbefore referred to, wherein an auxiliary inclined ram extension was used.

The underside of the dove-tailed slide 8 is in engagement with a spring cushioned plunger 18 housed in the bed of the machine in a proper manner, and by this means the slide is returned to its normal position in 50 readiness to be again engaged by the ram.

While the present improvement could be utilized, if desired, to punch nuts from the outside in, it is nevertheless particularly designed to punch the nuts from the inside out, since this is the preferable way of 55 castellating nuts in that it has very material advantages, and therefore it will be obvious that with the punch in the position shown in Fig. 6, which is its normal position before being shifted by the ram, the nut will be fed into the bore of the die, and thus be in such position that the cutting or punching end of the punch will project into the bore of the 60 nut. Thereupon, as the ram strikes the dove-tailed slide, the punch will be shifted 65

downwardly, as illustrated in dotted lines in Fig. 6 to castellate the nut, and by means of the spring cushioned plunger 18 the punch will be immediately shifted backwardly through the slot or castellation just made in 70 the nut, so that it will then be in the position shown in full lines in Fig. 6, whereupon the nut is indexed for the same operations to take place as before. Should it be desired to use this improved mechanism to castellate 75 nuts from the outside in, this could be done by merely changing the relative positions of the nut blank carrier, and punch, but there are numerous advantages for punching a nut from the inside out, one of which is that it 80 leaves no burrs adjacent to the threads of the nut.

It will be observed from the foregoing that neither the punch nor the die are connected in any way with the ram, or the ram 85 slide, or with the belt driven shaft, and therefore any lost motion of the ram or the ram slide does not in any way affect the action of the punch, and that the application of the force of the ram on the punch through 90 the medium of the vertically movable slide is brought on the entire punch, which is supported horizontally of the slide, and owing to the improved organization of this machine, a one and one-half inch or less stroke of the ram is sufficient to effectively do 95 the work of punching and indexing a blank successively to castellate it. As the movements are thus very short, they consequently 100 can be made very rapidly, which results in decided economy of time and production.

From the foregoing, it will therefore be seen that by having a cutting tooth extending forwardly of the front end of the body of the punch, which body front end is shown 105 substantially parallel with the front face of the blank, the body of the punch can be made of considerable size and of larger size than the opening of the blank right up to the tooth itself, and thus firmly and efficiently support the tooth where the strain is the greatest, while the tooth can be made of very small size and so enable the smallest kind of nuts to be castellated from the inside out, which has not heretofore been practicable, where a part of the body and the cutting portion of the punch had to enter the 110 opening in the blank, except by making the punch so small that its life was very much shortened.

Furthermore by the present construction it will be observed that the horizontally supported punch is carried by a vertically movable slide and this punch is supported right up to the tooth so that under the force of the ram there is no opportunity for the cutting end of the punch to spring upward.

It will be understood that the various details may be more or less modified without departing from the spirit or scope of the 120

claims, and that for instance, it is immaterial whether the nut blank be itself rotated independently of or with a carrier or whether the nut blank carrier when such is used, be indexed from the outside, as in my contemporaneously pending application No. 507,661 filed herewith, or from the inside, as in the said patent hereinbefore referred to, as such details do not materially affect the operation of the improved punching mechanism herein shown and described.

I claim as my invention:

1. The combination of a blank holder, a vertical reciprocating slide, a horizontally extending shaft housed in said slide, a horizontally extending punch housed in said shaft and having a projecting portion normally extending into the center opening of the blank, and a reciprocating ram engaging said slide for reciprocating the same.

2. The combination of a blank holder, a vertically reciprocating slide, a horizontally extending shaft housed in said slide, a horizontally extending punch housed in said shaft and having a forwardly projecting cutting tooth normally extending into the center opening of the blank, and means for vertically reciprocating said slide.

3. The combination of a blank holder, a vertically reciprocating slide, a horizontally extending shaft housed in said slide, a horizontally extending punch housed in said shaft and having a cutting projection of relatively small size normally extending into the center opening of the blank, means for reciprocating said slide, and means accessible from the rear end of said shaft for adjusting the position of said cutting projection within the blank.

4. The combination of a blank holder, a vertically reciprocating slide, a horizontally extending shaft housed in said slide, a horizontally extending punch housed in said shaft and having a projecting portion normally extending into the center opening of the blank, and means engaging said slide for reciprocating the same to cause said punch to castellate the blank from the center opening outwardly while the longitudinal axis of the blank is in horizontal position.

5. The combination of a blank holder adapted to hold blanks to be castellated, a punch support mounted for vertical sliding movement and having a bore, the axis of which normally coincides with the axis of the blank holder, a horizontally extending punch located in said bore and comprising a body portion and a forwardly projecting cutting tooth of less size than the diameter of the body portion and adapted to enter the center opening of the blank for castellating the blank from the inside out, said punch body being supported along its length up to said cutting tooth, and means for vertically reciprocating said punch support.

6. The combination of a blank holder adapted to hold blanks to be castellated, a punch support mounted for vertical sliding movement and having a bore, the axis of which normally coincides with the axis of the blank holder, a horizontally extending punch located in said bore and comprising a body portion and a forwardly projecting cutting tooth of less size than the diameter of the body portion and adapted to enter the center opening of the blank for castellating the blank from the inside out, said punch body being supported along its length up to said cutting tooth, means for vertically reciprocating said punch support, and means for adjusting said punch from the rear end thereof.

7. The combination of a blank holder adapted to hold blanks to be castellated, a punch support mounted for vertical sliding movement, a punch carried thereby and comprising a body portion having its front end substantially parallel to the front face of the blank and of larger diameter than the diameter of the blank opening and having a forwardly projecting cutting tooth of less size than the diameter of the body of the punch and the blank opening and adapted to extend into the blank opening, and means for vertically reciprocating said punch support thereby to punch a slot in the blank from the inside out.

8. The combination of a blank holder adapted to hold blanks to be castellated, a horizontally located punch, the longitudinal axis of which normally coincides with the axis of the blank holder, said punch having its front end of greater diameter than the opening of the blank and having a forwardly projecting cutting tooth of less size than the front end of the punch and the blank opening, means for supporting said punch horizontally along its length up to said cutting tooth, and means for vertically reciprocating said punch supporting means and blank holder one relatively to the other thereby to castellate the blank from the inside out.

9. The combination of a blank holder adapted to hold blanks to be castellated, a vertically sliding punch support, a punch carried by said support and extending horizontally therethrough and comprising a body having a substantially uniform cross section from end to end and greater than the diameter of the blank opening, and a forwardly projecting horizontal cutting tooth extending from the front end of said punch body and of less size than the blank opening and projecting thereinto, and means for vertically shifting said support and thereby the punch to castellate the blank.

10. The combination of a blank holder adapted to hold blanks to be castellated, a vertically reciprocating slide, a horizontally

extending punch carried by said slide in line with the opening of the blank and having a cutting tooth projecting forwardly of the end thereof and normally extending into the center opening of the blank for castellating the blank from the inside out, and a reciprocating ram engaging said slide for reciprocating the same.

11. In a nut castellating machine, the combination of a nut blank supporting means, means for indexing the blank, a punch supporting means comprising a hollow member and a vertically movable slide therefor, means for engaging said slide for forcing the punch into engagement with the blank thereby to castellate it, and means for adjustably positioning the punch within the hollow member and comprising an adjustable screw and a filler member.

12. In a nut castellating machine, the combination of a nut blank supporting means, means for indexing the blank, a punch supporting means comprising a hollow member and a vertically movable slide therefor, means for engaging said slide for forcing the punch into engagement with the blank thereby to castellate it, means for adjustably positioning the punch within the hollow member, and means for adjustably positioning the vertically movable slide.

13. In a nut castellating machine, the combination of a nut supporting means, means for indexing the blank, a punch supporting means comprising a vertically movable slide, a shaft supported horizontally therein and adapted to carry a round punch, and a shiftable ram for engaging said slide thereby to carry said punch into engagement with the blank to castellate it.

14. In a nut castellating machine, the combination of a nut blank supporting means, means for indexing the blank, a punch supporting means comprising a vertically movable slide, a shaft supported horizontally therein and adapted to carry a round punch, a shiftable ram for engaging said slide thereby to carry said punch into engagement with the blank to castellate it, means carried by the shaft for positioning the punch therein, and means carried by the slide for positioning the shaft therein.

15. The combination of a blank holder, a

support, a punch body extending horizontally therethrough and having a substantially uniform cross section from end to end 65 and greater than the diameter of the blank, a horizontal cutting projection extending forwardly from the end of said body and of less size than the blank opening to project thereinto, means for shifting said punch 60 body endwise relatively to said support to adjust the relative position of the cutting projection and blank, and means for shifting said punch body to castellate the blank.

16. In a nut castellating machine, the combination of a nut blank supporting and indexing means, means for locking the blank in its indexed position, means for feeding the blank to the supporting means, a ram, a vertically movable slide cooperating with 70 said ram, a punch supported by said slide in a horizontal position, and a hollow shaft carried by said slide for supporting said punch.

17. In a nut castellating machine, the combination of a nut blank supporting and indexing means, means for locking the blank in its indexed position, means for feeding the blank to the supporting means, a ram, a vertically movable slide cooperating 80 with said ram, a punch supported by said slide in a horizontal position, a hollow shaft carried by said slide for supporting said punch, means for positioning the shaft within the slide, and means for adjusting 85 the punch relatively to the shaft.

18. In a nut castellating machine, the combination of blank supporting means, means for indexing it, means for locking the blank supporting means, means for feeding a blank to the blank supporting means, a reciprocating ram, a vertically movable dove-tailed slide shiftable by said ram, said slide having a horizontally located bore therein, the axis of which is coincident with the axis of the blank supporting means, and a hollow shaft located in the bore of said slide and adapted to carry a horizontally located punch effective to punch blanks from the inside out. 100

Signed at Cleveland, Ohio, this 12th day of October, 1921.

OSCAR A. SMITH.
